UNITED STATES PATENT OFFICE.

CHRISTIAN B. LONGENECKER, OF PHILADELPHIA, PENNSYLVANIA.

CARBON-REMOVER.

1,101,646.

Specification of Letters Patent. Patented June 30, 1914.

No Drawing.

Application filed October 4, 1913. Serial No. 793,339.

To all whom it may concern:

Be it known that I, CHRISTIAN B. LONGENECKER, citizen of the United States, residing at Philadelphia, in the county of Philadelphia and State of Pennsylvania, have invented certain new and useful Improvements 5 in Carbon-Removers, of which the following is a specification.

This invention relates to a composition of 10 matter, put up in dry form and preferably compressed into tablets or pellets for convenient use, said composition being adapted, when inserted into the heated cylinder of an internal combustion engine, and while the 15 engine is thereafter in operation, to cause the carbon deposits on the walls of the cylinder to loosen and pass out with the exhaust gases; to lubricate the cylinder, and to give a peculiar odor to the exhaust gases while 20 the carbon removing elements are in the cylinder, whereby it may be determined, by the absence of the peculiar odor, when said elements have passed out with the exhaust.

In carrying out my invention, I take suitable proportions of a sodium salt, sulfur, and pure graphite, and thoroughly mix the same by any well known means, and this mixture is, by means of dies, compressed into tablets of suitable size for insertion 30 through the spark plug openings in the cylinders of internal combustion engines. I have found in practice that a very effective compound for the purpose stated is made by using the above mentioned elements or 35 ingredients in approximately the following proportions by weight: sodium chlorid, 81 parts, sulfur, 12 parts, and graphite, 3 parts; also sodium chlorid, 40 parts, sodium carbonate, 40 parts, sulfur, 12 parts, and graphite, 3 parts. While these proportions are preferred, I do not confine myself thereto. Either sodium chlorid alone, or sodium carbonate alone, or a mixture of the two, may be used with the other ingredients.

40 The relative proportions of the sodium salt to sulfur may be varied considerably, with more or less satisfactory results. Thus, in the illustration just given the carbon-removing elements, sodium salt and sulfur, are in 45 the proportions, one to the other, of 87 per cent. of the salt and 13 per cent. sulfur. The relative proportions of these two ingredients may vary from 60 per cent. salt to 40 per cent. sulfur, to 95 per cent. salt and 5 per 50 cent. sulfur. Whatever the relative proportions of the carbon removing elements,

the lubricating element, graphite, will only be a small percentage of the entire mass, and may be the same for all mixtures.

In using the tablets or pellets, the engine 60 is operated until the cylinders are hot. Then the spark plug is removed from one cylinder and a suitable number of tablets,—say five or six 24 grain tablets—is inserted through the spark plug opening into the 65 cylinder and the plug is then replaced and the engine is then started. The sodium salt and the sulfur, under the action of the heat, combine with the carbon and operate to chemically disintegrate and loosen the 70 carbon deposits within the cylinder, which pass out with the exhaust gases. The graphite, which does not change with the heat, remains, largely, in the cylinder and serves as a lubricant for the piston. The 75 sulfur gives a peculiar odor to the exhaust gases and serves as a tell-tale to indicate, by the absence of the odor, when the carbon removing elements of the compound have been practically exhausted from the cylinder. It 80 is desirable to treat only one cylinder at a time, as the explosions may not take place regularly in the cylinder under treatment. It can be determined from the absence of the peculiar odor before mentioned when the 85 compound has ceased to act in one cylinder, and the engine may then be stopped and treatment applied to the next cylinder, and so on until all of the cylinders of the engine have been treated.

90 As the compound is in the form of dry tablets, it is convenient to handle and the amount of material required, as determined by experience or the condition of the cylinder, can readily be selected and inserted in 95 the cylinder.

What I claim is:

1. A compound for treating cylinders of internal combustion engines comprising a sodium salt and sulfur in the proportions 100 of from 60 to 95 per cent. of the former to 40 to 5 per cent. of the latter.

2. A compound for treating cylinders of internal combustion engines comprising a sodium salt and sulfur in the proportions 105 of from 60 to 95 per cent. of the former to 40 to 5 per cent. of the latter, and a small quantity of dry lubricant.

3. A compound for treating cylinders of internal combustion engines comprising a 110 sodium salt and sulfur in approximately the proportions of 87 per cent. of the former to

13 per cent. of the latter, and a small quantity of dry lubricant.

4. A compound for treating cylinders of internal combustion engines comprising sodium chlorid and sulfur in the proportions of from 60 to 95 per cent. of the former to 40 to 5 per cent. of the latter.

In testimony whereof I have affixed my signature, in presence of two witnesses.

CHRISTIAN B. LONGENECKER.

Witnesses:

ROBERT WATSON,
EFFIE R. LONGENECKER.
